(57) CLAIM

The ornamental design for an attachable folding half heart shaped trinket, as shown and described.

DESCRIPTION

FIG. 1 is a front view of an attachable folding half heart shaped trinket showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front view of the cover opened thereof;

FIG. 8 is a front view showing the second variation of the attachable folding half heart shaped trinket according to the design having a band on a cover;

FIG. 9 is a rear view thereof;

FIG. 10 is a left side view thereof;

FIG. 11 is a right side view thereof;

FIG. 12 is a top view thereof;

FIG. 13 is a bottom view thereof; and,

FIG. 14 is a front view of the cover opened thereof.
